(57) **CLAIM**

The ornamental design for a female connector in a patient temperature control system, as shown and described.

DESCRIPTION

FIG. 1 is a perspective view of one side of the female connector in a patient temperature control system;

FIG. 2 is a front view of the female connector in a patient temperature control system;

FIG. 3 is a back view of the female connector in a patient temperature control system;

FIG. 4 is a right side view of the female connector in a patient temperature control system;

FIG. 5 is a left side view of the female connector in a patient temperature control system;

FIG. 6 is a top view of the female connector in a patient temperature control system;

FIG. 7 is a bottom view of the female connector in a patient temperature control system;

FIG. 8 is a perspective view of a second embodiment of the female connector in a patient temperature control system;

FIG. 9 is a front view of a second embodiment of the female connector in a patient temperature control system;

FIG. 10 is a back view of a second embodiment of the female connector in a patient temperature control system;

FIG. 11 is a right side view of a second embodiment of the female connector in a patient temperature control system;

FIG. 12 is a left side view of a second embodiment of the female connector in a patient temperature control system;

FIG. 13 is a top view of a second embodiment of the female connector in a patient temperature control system; and,

FIG. 14 is a bottom view of a second embodiment of the female connector in a patient temperature control system.

The broken line showing in the FIGS. 1 through 14 are for illustrative purposes only and forms no part of the claimed design.
